UNITED STATES PATENT OFFICE

BENJAMIN H. FALKNER, OF AURORA, ILLINOIS, ASSIGNOR, BY DIRECT AND MESNE ASSIGNMENTS, TO WESTERN WHEELED SCRAPER COMPANY, OF AURORA, ILLINOIS, A CORPORATION OF ILLINOIS

TRACK LINER

Application filed August 20, 1926. Serial No. 130,422.

The present invention relates to track liners, such as are commonly employed for lining railway tracks.

The primary object of the invention is to provide a track liner in the form of a simple, compact unit, much in the nature of an accessory, adapted for instant association with a conventional type of a track lifting jack, whereby a simple, efficient track liner is formed. In this tool the jack functions to produce the required force or pressure to move the track, and the present unit serves to convert the lifting motion of the jack into a lateral shifting motion applied to the track for lining the same. The conventional track lifting jack is always a standard part of the equipment of a railway section gang, and by the provision of the present unit such jack is made useable for the lining of tracks, as well as for track lifting. There is thus avoided the expense and inconvenience of carrying a special track liner, which is generally a heavy, cumbersome tool, and which only has the single utility of lining track.

In the accompanying drawings illustrating a preferred embodiment of my invention:

Fig. 1 is a side elevational view of the present device in use, showing a standard track lifting jack in place thereon;

Fig. 2 is a perspective view of the present device with the track jack removed;

Fig. 3 is a plan view of the same; and

Fig. 4 is a transverse sectional view taken approximately on the plane of the line 4—4 of Fig. 2.

The unit comprises a base or support 5 adapted for resting on the road bed between the ties. The inner end of this base, corresponding to the end adapted to pass under the rail 6, is slotted longitudinally, as indicated at 7, to divide this inner end into two substantially parallel arms 8, 8 having bosses 9 at their ends. A lining bar 10 is pivotally supported between these arms on a heavy pivot pin 11 passing through the bosses 9. The arms 8 are ribbed at 12 to reinforce them against bending stresses.

Rising upwardly from the other end of the horizontal base plate 5 is an inclined support or mounting seat 13 for receiving the

base of a standard track lifting jack 14. This inclined support is provided with suitable means for detachably seating and holding the base of the jack, as I shall presently describe. An end wall 15 extends downwardly from the outer end of the inclined wall 13 and joins the base 5. Preferably a flange 16 extends downwardly from the rear end of the base 5 to engage in the ballast of the track bed so as to prevent the unit from shifting away from the rail 6 under the stress of lining the track. It will also be observed that the entire area of the end wall 15 can serve as an abutment surface for reacting against the earth or rock ballast constituting the road bed. If desired, suitable flanges or gripping points may be disposed along the under side of the base 5 for additional anchorage, but I have found that the construction disclosed is adequate for maintaining a firm anchorage in any road bed.

In order that the unit be of minimum weight for low cost and ready portability the sloping surface 13 is preferably constructed as an open frame. For example, the intermediate portion of this inclined support is left open, as indicated at 17, and the reinforcement of such supporting surface is obtained by two ribs 18 formed integral with the under side of this sloping surface and with the end and bottom walls of the unit. Such end and bottom walls are also provided with openings 19 and 20, a cross web 21 in the upper part of the end wall re-enforcing the two side portions of this open support against outward stresses.

The standard construction of track lifting jack generally has an extended base 22 from which project lateral flanges 23. To detachably mount and hold the jack on the inclined support 13 I have provided two marginal flanges 24 formed along the lateral edges of the supporting surface 13, these marginal flanges having inwardly turned flange portions 24'. The laterally extending base flanges 23 of the jack are adapted to slide in between the marginal flanges 24 and to be held against vertical displacement or rocking movement on the support by the engagement of the hook-like flange portions 24'.

over the base flanges of the jack. Thus the flanges 24, in conjunction with the sloping surface 13, constitute in effect an inclined socket into which the base of a standard track lifting jack can be readily inserted.

The lifting element in this type of jack is generally in the form of a projecting foot or lug 25 extending outwardly from the standard of the jack and moving up and down in 10 a slot in the lower part of this standard.

In the operation of lining a track, the present unit is placed between the ties at any desired point along the rail, and either on the inside or the outside thereof. In the placing 15 of the unit the pivot end 11 is located under the rail 6, either directly below or slightly beyond the rail. It will be observed that the unit is of relatively low height so that in many instances it can be forced under the rail 20 without the necessity of digging out between the ties, but even where this digging out is necessary only a shallow excavation is required because of the relatively shallow depth of the unit. After the unit has been properly 25 located under the rail, the base of the track lifting jack 14 is slipped in between the flanges 24 on the inclined supporting surface 13 with the lifting foot 25 engaging under the end of the lining bar 10. Thereupon, 30 operation of the jack will result in the lining bar converting the upward lifting movement of the foot 25 into a combined lifting and thrusting pressure applied laterally to the rail 6. Because the bar 10 engages the rail 35 between its pivots and its free end it operates with a mechanical advantage and this, together with the mechanical advantage of the jack will result in the shifting of the track laterally with the application of a relatively 40 small effort on the jack handle. By virtue of the angle of the jack relative to the swinging movement of the lining bar, the latter will remain in engagement with the lifting foot 25 through a considerable part of its upward travel, whereby a considerable throw 45 can be given the track before any resetting of the device is necessary.

While, according to the preferred embodiment, the unit is constructed to receive a 50 standard type of track lifting jack, it is within the purview of the invention to construct the unit otherwise. For example, for commercial reasons, it might be desirable to construct the unit so that it would only receive a specially designed jack also marketed by the manufacturer of the unit, such jack, however, being removable from the unit 55 so that it could also be used for ordinary track lifting operations.

60 What I claim as my invention and desire to secure by Letters Patent, is—

1. A track liner comprising a base adapted for setting in the road bed adjacent the track, an inclined support on said base adapted detachably to mount a track lifting jack, and a

lining bar pivoted to said base and adapted to be revolved in a path extending transversely of the track through actuation of said jack.

2. A track liner comprising a base adapted 70 for setting in the road bed adjacent the track, socket means on said base adapted detachably to receive and support a track lifting jack, and a lining bar pivoted to said base and adapted to engage a lifting foot on said jack 75 for pivotal movement in the actuation of said jack.

3. A track liner comprising a base for setting in the road bed adjacent the track, an inclined support on said base having hook 80 like flanges adapted to engage over the base of a track lifting jack, said jack being removably mounted on said support, and a lining bar pivoted to the other end of said base and having its free end adapted to engage the 85 lifting foot of the jack, whereby actuation of the jack results in said lining bar swinging upwardly and laterally relative to the track.

4. In track lining means, a base having a support adapted for reception of the base 90 flange of a lifting jack and provided with elements disposed and adapted for engagement over said base flange, and a lining bar pivoted at one end to said base and of a length to rest upon the lifting foot of the jack. 95
